CLOSURE SEAL

John W. Watson, Evanston, Ill., assignor to The Hydro-Blast Corporation, Chicago, Ill., a corporation of Illinois

Application February 12, 1952, Serial No. 271,226

3 Claims. (Cl. 220—46)

This invention relates to dewatering devices for granular material and more particularly to the construction of the casing and seal for a dewatering device to prevent the loss of material during operation.

It has been proposed in the copending application of Roderick S. Webster, Serial No. 136,349, filed December 31, 1949, now Patent No. 2,644,587, to dewater granular material such as sand by confining it in a casing having a perforated bottom closure and forcing water therefrom by a gaseous medium under pressure.

This operation has been highly successful, but a difficulty has been encountered in maintaining a proper seal between the bottom of the casing and the closure to prevent material from leaking therebetween during operation. Experience has shown that when granular material such as sand is wet, it flows very readily and even though the sealing surfaces are carefully formed, granular material may accumulate therebetween to leave openings through which the material can leak.

It is accordingly one of the objects of the present invention to provide a dewatering device for granular material in which an effective seal is produced between the casing bottom and the closure to prevent leakage of granular material therebetween during operation.

Another object is to provide a dewatering device in which the seal between the casing bottom and the closure is self cleaning to insure proper sealing therebetween regardless of accumulations of granular material on the surfaces.

Still another object is to provide a dewatering device in which the seal is formed by an annular elastic strip which is arranged to wipe over the closure during closing movement thereon and again to wipe over the closure when the casing is subjected to pressure thereby to insure a good seal.

A further object is to provide a dewatering device in which the sealing strip is easily and securely mounted in the casing by means of an expansible ring.

The above and other objects and advantages of the invention will be more readily apparent when read in connection with the accompanying drawings in which:

Figure 1 is a partial section through the bottom part of a dewatering device embodying the invention showing the closure in open position;

Figure 2 is a view similar to Figure 1 showing the position of the parts with the closure closed but no pressure in the casing; and

Figure 3 is a view similar to Figure 2 showing the position of the parts with pressure in the casing.

The apparatus as illustrated comprises a casing or container 10 of vertical tubular form and which preferably has a smooth inner cylindrical surface to receive wet granular material which is to be dewatered. At its lower end the outer surface of the casing is bevelled as indicated at 11 so that the casing terminates in a relatively sharp edge and so that its inner surface continues as a smooth cylinder completely to the bottom thereof.

The bottom of the casing is adapted to be closed by a

2

perforated closure shown as comprising an outer annular ring 12 open in its center and supporting a screen 13 in its center portion. The ring 12 is of such a diameter and width that it will seat on the lower edge of the casing and will project radially both inwardly and outwardly beyond the casing edge with the screen 13 lying only in the central part of the casing bottom.

In order to effect a tight seal between the closure and the casing, there is provided according to the present invention an annular strip 14 of elastic material such as rubber which is normally of a slightly smaller diameter than the casing interior. The strip 14 is secured in the lower end of the casing above the bottom thereof by the annular expansible ring 15, whose ends are connected by an adjustable reverse threaded screw 16 so that the diameter of the ring can be varied. To mount the seal, the ring 15 is slipped into one end of the annular strip 14 and the assembly is then inserted in the bottom of the casing to a point such that the lower edge of the ring will be spaced above the casing bottom as shown. The ring is then expanded by turning the screw 16 to press the sealing strip tightly against the casing inner wall to effect a tight seal therebetween and to hold the sealing strip and the ring in place in the casing by friction. When so mounted, the lower edge of the sealing strip 14 curves inwardly and downwardly as shown in Figure 1 to a point normally below the bottom edge of the casing.

When the closure is moved to its closed position as illustrated in Figure 2, the lower edge of the sealing strip 14 will engage the closure ring 12 and as the closure moves toward the casing the sealing strip will be bent upward so that its lower edge will wipe radially inward over the closure. Thus, any granular material left on the closure will be wiped therefrom under the edge of the sealing strip to leave a clean surface against which the strip can seal. The relatively sharp lower edge of the casing 10 produced by the bevel 11 will bite through and spread any accumulations of granular material between it and the closure to enable movement of the closure into firm engagement with the casing bottom.

When pressure is applied to the interior of the casing to force water from the granular material therein, the flexible sealing strip 14 will be stretched and expanded to the position shown in Figure 3. During this movement the inner lower edge of the strip will wipe radially outward across the closure to wipe out any granular material therebetween so that a good sealing contact will be obtained. As finally expanded, the sealing strip will consist of two substantially right angular portions one of which lies flat against the inner surface of the casing and the other of which lies flat against the closure. In this way a tight seal is formed between the casing and the closure which will prevent loss of any material therebetween, even when subjected to relatively high pressure and with the granular material in an extremely wet and flowable condition.

While one embodiment of the invention has been shown and described in detail, it will be understood that it is illustrative only and is not to be taken as a definition of the scope of the invention, reference being had for this purpose to the appended claims.

What is claimed is:

1. A dewatering device for granular material comprising a vertical casing open at its bottom and having a smooth cylindrical inner surface, the bottom of the casing terminating in a tapering relatively sharp edge, a flat closure for the bottom of the casing movable against said edge and a tubular strip of elastic material secured to the inner wall of the casing above the bottom thereof and normally extending downward and inward from its line of attachment to a level below the casing bottom to

engage and wipe radially inward over the closure when it is moved into engagement with said edge.

2. A dewatering device for granular material comprising a vertical casing open at its bottom and having a smooth cylindrical inner surface, the bottom of the casing terminating in a tapering relatively sharp edge, a flat closure for the bottom of the casing movable against said edge, and a tubular strip of elastic material secured to the inner wall of the casing above the bottom thereof and normally extending downward and inward from its line of attachment to a level below the casing bottom to engage and wipe radially inward over the closure when it is moved into engagement with said edge, pressure in the casing stretching the strip into engagement with the casing wall and causing the lower edge thereof to wipe radially outward over the closure.

3. A dewatering device for granular material comprising a vertical casing open at its bottom and having a smooth cylindrical inner surface, the bottom of the casing terminating in a tapering relatively sharp edge, a flat closure for the bottom of the casing movable against said edge, a tubular elastic strip normally of smaller

diameter than the casing fitting in the casing an expandable ring fitting within the strip and means to expand the ring to cause it to press the strip against the inner casing wall at a level above the bottom of the casing, the strip being of a width to project radially inward and downward from the ring to a level below the bottom of the casing.
